UNITED STATES PATENT OFFICE.

ALFRED E. SELIGER, OF NEWARK, NEW JERSEY.

DESIGN FOR A BOX.

SPECIFICATION forming part of Design No. 22,113, dated January 10, 1893.

Application filed November 25, 1892. Serial No. 453,136. Term of patent 3½ years.

To all whom it may concern:

Be it known that I, ALFRED E. SELIGER, a citizen of the United States, residing at Newark, in the county of Essex and State of New Jersey, have invented and produced a new and original Design for a Box having an Ornamental Lid, of which the following is a specification, reference being had to the accompanying drawing, forming a part thereof.

10 This design relates to a new and original design for a box, having as a special feature an ornamental lid provided in bas-relief thereon with a representation of the Electrical Building of the World's Columbian Exposition, and a raised scalloped ornamentation arranged around said bas-relief.

15 In the drawing herewith accompanying, the figure represents a perspective view of a box having the ornamental lid provided with the 20 design thereon, which view is deemed sufficient to illustrate the leading features of the design.

25 The design is composed of two distinct elements to insure the beauty of the article. These consist, first, in the box provided with the lid, having in bas-relief thereon a representation of the Electrical Building of the World's Columbian Exposition, and second, in

arranging around the paneled top of the lid and the said bas-relief a raised scalloped ornamentation. The beauty and effect of the design are therefore due to these features, and the leading features of the design reside in the box provided with a lid having the ornamentation as illustrated. 30

35 Referring to said view, *a* is the paneled or smooth open field of the lid of the box in which is arranged in bas-relief a representation of the Electrical Building of the World's Columbian Exposition and arranged around 40 the same is a raised scalloped ornamentation *b* harmonizing with the surrounding edge of the paneled lid. These are the essential features of my design.

What I claim, and desire to secure by Letters-Patent is:

The design for a box provided with a lid having the ornamentation thereon, substantially as herein described and shown.

In testimony that I claim the invention set forth above I have hereunto set my hand this 22d day of November, 1892.

ALFRED E. SELIGER.
